MEASURING CUP

T. Carroll Wilson, Piedmont, Calif., assignor to Hills Bros. Coffee, Inc., San Francisco, Calif., a corporation of California

Application May 11, 1953, Serial No. 24,930

Term of patent 14 years

(Cl. D44—9)

Fig. 1.

Fig. 2.

Fig. 5.

Fig. 3.

Fig. 4.

To all whom it may concern:

Be it known that I, T. Carroll Wilson, a citizen of the United States, residing at Piedmont, county of Alameda, State of California, have invented a new, original, and ornamental Design for Measuring Cup, of which the following is a specification, reference being had to the accompanying drawing, forming a part hereof.

Fig. 1 is a perspective view of a measuring cup, showing my new design;

Fig. 2 is a top plan view;

Fig. 3 is a bottom plan view;

Fig. 4 is a side elevational view; and

Fig. 5 is a vertical sectional view through the body of the measuring cup.

I claim:

The ornamental design for a measuring cup, as shown.
